UNITED STATES PATENT OFFICE

162,424

SILVERWARE CABINET

Charles W. Kulp, Meriden, Conn.

Application October 28, 1949, Serial No. 5,743

Term of patent 7 years

(Cl. D33—19)

To all whom it may concern:

Be it known that I, Charles W. Kulp, a citizen of the United States and resident of Meriden, in the county of New Haven and State of Connecticut, have invented a new, original, and ornamental Design for a Silverware Cabinet, of which the following is a specification, reference being had to the accompanying drawing, forming a part thereof.

In the drawing, Fig. 1 is a front perspective view of a silverware cabinet showing my new design; Fig. 2 is a side view thereof, and Fig. 3 is an enlarged perspective view thereof, with the doors open and showing the interior of the cabinet.

I claim:

The ornamental design for a silverware cabinet, substantially as shown.

CHARLES W. KULP.
